SHOE CONSTRUCTION

George E. Musebeck, Nashotah, and John C. Boehm, Belgium, Wis., assignors to Musebeck Shoe Company, Oconomowoc, Wis., a corporation

Application September 2, 1950, Serial No. 183,013

2 Claims. (Cl. 36—76)

1

The present invention relates to improvements in footwear and more particularly the invention relates to improvements in the insoles for shoes.

The invention has for one of its objects that of providing a shoe having an insole which is so constructed as to provide for the support of both the longitudinal arch and the metatarsal arch of the foot.

It has been found desirable to provide a relatively rigid support for the longitudinal arch of the foot, which would prevent the displacement or falling of the arch in normal activities.

It is therefore one of the objects of the present invention to provide a relatively rigid support which will occupy comparatively little space on the insole of a shoe and which may be made of comparatively light material.

For the purpose of disclosing the invention we have illustrated an embodiment of our invention in the accompanying drawings in which

Fig. 1 is a top plan of a sole embodying our invention.

Fig. 2 is a sectional view taken on the line 2—2 of Fig. 1 showing in addition thereto a portion of the upper of the shoe attached thereto.

Fig. 3 is a perspective view of the reinforcing shank stiffener.

Fig. 4 is a top plan view showing a portion of the sole as in Fig. 1 with the reinforcing shank stiffener and fabric strip removed for clearness.

In the structure illustrated there is provided an insole 10 having an arch supporting extension 11. The insole may be scored transversely at the ball thereof as at 12 to give greater flexibility thereto at this point.

Secured to the face of the insole constituting the bottom face thereof when assembled in a shoe structure is a second piece 13 of the same material as the insole and of substantially the same thickness. This piece 13 at its outer edge follows the normal contour of the insole without the arch extension 11 and the inner edge 14 of the piece 13 is straight, following approximately the longitudinal center line of the insole.

The forward edge 15 of the piece 13 extends to approximately the ball of the insole and is scarfed to provide a gradual reduction of the thickness thereof at this point. The rear end of the piece 13 extends to a point 16 of the heel and this rear end is also slightly scarfed to provide a gradual reduction in the thickness of the material. The two edges of the rear end are preferably curved towards one another as indicated so that the rear end is pointed with the point terminating at the outer edge of the heel.

2

The piece 13 may be secured to the insole by cementing and by rivets 17.

A second piece 18 is secured to the bottom face of the insole of substantially the same thickness as the piece 13. The inner edge 19 of this piece is straight and extends parallel with the inner edge of the piece 13 being slightly spaced apart therefrom to provide a channel 20. The outer edge of the piece 18 follows the contour of the outer edge of the insole 10. The piece 18 extends forwardly to the point 21 which is substantially transversely parallel with the end 15 of the piece 13.

The rear end of the piece 18 extends to the point 22 substantially at the breast of the heel. Preferably the front end of the piece 18 is curvily inclined at the point 23. This piece like the piece 13 may be secured to the inner sole by cementing and by suitable rivets like the rivets 17.

The edge of the inner sole 10 from the front end of the piece 13 forwardly and around the toe portion to the front end of the piece 18 is slit with the slit portion turned up to provide a stitching flap 24. Inside of said cut a stitching channel is cut in the usual manner which channel terminates with the cut. The outer edges of the pieces 13 and 18, as well as the inner sole proper, are channelled as at 25 and 26 to provide stitching flaps. However, in practice the channels 25 and 26 and recesses are cut on the usual channeling machine before they are assembled on the insole. Reinforcing fabric strip 27 is secured by gluing and stitching in the stitching channel and flaps.

An additional arch brace in the form of a sheet metal plate 28 is provided which strip or brace has a rib 29 formed therein and when the plate is assembled on the bottom face of the pieces 13 and 15 the rib lies in the channel 20 between the spaced edges of the strips.

This brace may be secured in position at its rear end by a peg or screw passing through an opening therein and into the heel portion of the inner sole but not far enough to pass through the inner sole.

In assembly the channel between the pieces 13 and 15 is filled with a plastic material adapted to harden such as sawdust mixed with pyroxylin cement. The bracing plate is then placed in position with the rib embedded in the cement and after the cement has hardened the resulting structure provides a strong support for the foot arch.

The insole constructed as above then has the welt 30 secured thereto and the upper 31 secured to the welt in the usual manner.

It is to be noted that the strip or piece 13 extends beneath the scaphoid portion of the longitudinal arch of the foot and that the entire structure provides a firm support for the entire length of the arch.

The invention claimed is:

1. An insole for shoes comprising an insole body having an arch supporting extension, a thickness of material secured on the bottom face of the insole and extending the length of the scaphoid portion of the longitudinal arch of the foot having its outer edge conforming to the edge of the insole, and a second thickness of material secured on the bottom face of the insole along side of said first piece having its outer edge conforming to the edge of the insole and the inner edge spaced apart from the first piece to provide a longitudinal groove following approximately the longitudinal center line of the insole and a rigid flap shank stiffener lying on the outer surface of said thicknesses and having a stiffening rib intermediate of its side edges centered in said longitudinal groove and extending towards the face of the insole, said insole and thicknesses having a stitching flap turned up therefrom.

2. An insole for shoes comprising an insole body having an arch supporting extension, a thickness of material secured on the bottom face of the insole and extending beneath the scaphoid

portion of the longitudinal arch of the foot and at least a portion of the inner portion of the heel and having a straight inner edge and the outer edge conforming to the edge of the insole, and a second thickness of material positioned along side said first piece having a straight inner edge spaced apart therefrom to provide a longitudinal groove following approximately the longitudinal center line of the insole and having its outer edge following the contour of the insole and a rigid flap shank lying the outer surface of said thicknesses and having a stiffening rib centered in said longitudinal groove and facing towards the inner sole, said inner sole and thicknesses having stitching flaps turned up therefrom.
